A. L. SESSIONS.
WASHING MACHINE.
APPLICATION FILED OCT. 26, 1911.

1,175,016.

Patented Mar. 14, 1916.

UNITED STATES PATENT OFFICE.

ALBERT L. SESSIONS, OF BRISTOL, CONNECTICUT.

WASHING-MACHINE.

1,175,016.

Specification of Letters Patent. Patented Mar. 14, 1916.

Application filed October 26, 1911. Serial No. 656,999.

To all whom it may concern:

Be it known that I, ALBERT L. SESSIONS, a citizen of the United States, and a resident of Bristol, in the county of Hartford and State of Connecticut, have invented a new and Improved Washing-Machine, of which the following is a specification.

My invention relates to the class of devices employed for the purpose of washing clothes, fabrics and the like by mechanical means, and the object of my invention, among others, is to provide a device of this class that may be readily attached to and detached from tubs or like devices of ordinary construction and that shall be simple in construction and effective in operation.

One form of device embodying my invention and in the use of which the objects above set out, as well as others, may be attained is illustrated in the accompanying drawings, in which—

Figure 1 is a plan view of a portion of a tub showing my improved washing apparatus attached thereto, the driving shaft being broken off. Fig. 2 is a view in vertical section through the device on a plane passing centrally through the agitating hood. Fig. 3 is a detail top view of the lower bracket. Fig. 4 is a view in elevation of the top bracket. Fig. 5 shows in detail the brackets for supporting one end of the shaft. Fig. 6 is a detail view in elevation of a modified form of agitating hood. Fig. 7 is a bottom view of the same.

In the accompanying drawings the numeral 6 denotes a tub of ordinary construction that may be supported upon standards 7, in the device herein shown there being two of these tubs separated by the usual wall 40 or partition 8.

In carrying out my invention I provide brackets which may be removably attached to the tub, one co-operating with the other to hold it in place, and these brackets having bearings and like supports for different parts of the apparatus. In that embodiment of the invention shown herein the numeral 9 denotes a bottom bracket arranged to embrace the lower edge of a tub as shown in Fig. 2 of the drawings, and the numeral 10 denotes a top bracket arranged to grasp the upper edge of the tub and to be located above the bottom bracket 9, a clamp rod 11 being suitably secured to one of the brackets 55 and projecting through a hole in the opposite bracket and secured as by a clamp nut

12. The bottom bracket has a lateral extension 13 and a bearing arm 14 extending downward from the bracket. A driving shaft 15 has its bearing in the arm 14 and is driven as by means of a belt 16 from a motor 17 passing around a pulley 18 secured to the driving shaft 15. An eccentric 19 or similar device is secured to the driving shaft 15 and operates a connecting rod, operatively engaging the eccentric at its lower end and connected with an agitator lever 21 at its upper end. This connecting rod is preferably formed in two sections 20 and 22, the recessed section 22 containing a spring 70 23 resting upon the bottom of the recess and thrusting against the section 20 of the rod. The upper end of the rod is adjustably connected as at 24 with the agitator lever.

The agitator lever is pivotally supported 75 on a stud 25 projecting from an arm 26 rising from the bracket 10, and is connected with an agitator stem 27 secured to an agitating hood 28. In the form of construction herein shown a sleeve 29 is pivotally secured 80 to a socket piece 30 mounted for adjustment longitudinally on the lever 21, the upper end of the agitator stem 27 extending within the sleeve and being held therein as by means of a holding screw 31 projecting into an 85 annular groove, (not shown), in the upper end of said stem, so that it may have a rotative movement within the sleeve while being held from lengthwise movement therein. This agitator stem also has a spiral groove 90 32 preferably formed in an enlargement therein, a pin 33 projecting from within the bearing 34 into said groove, said bearing being suitably supported by a bar 35 extending across the tub. From this construction 95 it will be seen that as the lever 21 is rocked the agitator stem will be raised and lowered, and by means of the spiral groove and pin will also be partially rotated in opposite directions, the connection between the upper end of said stem and the sleeve 29 being loose enough to permit rocking movement of the lever 21 and lateral play of the sleeve 29 without binding upon the stem 27.

The agitator 28 has a diaphragm 36 providing a chamber 37 in the upper end of the agitator with an outlet 38 controlled by a valve 39. There is also a vent opening 40 through the wall of the chamber 37 into a vent passage 41. A recessed projection 43 110 rises from the bottom of the tub and has openings 44—45 from within the recess to

the outside thereof, this projection preferably removably fitting within the tub at the bottom thereof. The agitator and projection may be of any desirable form in cross section, as round, rectangular, or otherwise.

A shaft 46 is mounted in the lateral projection 13 from the bracket 9 and also in a lateral projection 47 from the bracket 10, this shaft being driven as by means of a pinion 48 on the driving shaft 15 meshing with a pinion 49 on the connecting shaft 46. The upper end of the shaft bears a pinion 50 engaging with a pinion 51 on a cross shaft 52, the latter being employed to drive a wringer 53 secured to the tub, the cross shaft being suitably connected as by means of pinions 54—55 with a shaft 56 of the wringer. The ends of the driving and cross shafts opposite the brackets 9 and 10 are supported in brackets 57—58 that as shown in Fig. 5 of the drawings are of similar construction to the brackets 9 and 10, the arm 26 and lateral projection being omitted from the upper bracket, and the lateral projection from the lower bracket. In the form of agitator shown in Figs. 6 and 7 there is a projection 59 preferably extending lengthwise thereof, as particularly shown in Fig. 7.

To effectively remove the dirt from the articles the projection 43 is provided with ribs 42 located on the outer surface of the projection, as shown in Fig. 2.

While I have shown and described herein a preferred form of construction embodying my invention, this may be changed to a greater or less extent and yet embody my idea, and I do not therefore limit my invention to an apparatus constructed exactly as shown and described herein.

It will be noted that the beveled pinions are splined to the shafts to accommodate themselves to different positions of the attachments which they are to drive, these different positions of the attachments being caused by differences in the size of tubs, or otherwise.

I claim—

1. In combination with a tub, a pair of brackets arranged for coöperative removable attachment to the tub, the brackets each having bearings off-set from the plane of the brackets for the reception of a shaft, a shaft mounted in said bearings, a driving shaft mounted in one of said brackets and

positioned below said tub, a rock arm 55 mounted in the other bracket above the tub, and connections between the driving shaft and rock arm.

2. In combination with a tub, brackets arranged for attachment to the upper and lower edges of the tub, means for coöperatively removably attaching said brackets to the tub, a driving shaft supported by the lower bracket, means for operating said shaft, a lever supported by the upper bracket, and an operative connection between said lever and driving shaft.

3. In combination with a tub, a bracket arranged to be secured to the bottom of the tub and having a projection for a driving shaft, a driving shaft supported by said projection, means for operating the driving shaft, another bracket secured to the upper edge of the tub, coacting means upon the brackets for securing them together, an arm 75 rising from the upper bracket, a lever pivotally mounted on said arm, a connecting rod between the driving shaft and lever, an agitator located within the tub, a connection between said lever and agitator, and 80 means for imparting reciprocating rotary movement to said agitator in the vertical reciprocating movement thereof.

4. In combination with a tub, a pair of coöperating brackets arranged for removable attachment to the tub, means for securing the brackets to the tub, one of said brackets having an arm to support a driving shaft, another arm to support a connecting shaft, and the other of said brackets 90 having an arm to support the connecting shaft and an arm to support an operating lever, the operating lever pivotally mounted to said arm, and an agitator located within the tub and suspended from said arm. 95

5. In combination with a tub, a pair of brackets secured to the upper and lower edges thereof, a pair of extensions carried by each bracket, fastening means associated with coöperating ones of said extensions, a power shaft journaled in one of said lower extensions, a rock arm carried by one of the upper extensions, and a connecting member between the rock arm and power shaft.

ALBERT L. SESSIONS.
